METHOD OF AND MEANS FOR DISTILLING COAL.

1,422,706.

Specification of Letters Patent. Patented July 11, 1922.

Application filed September 18, 1919. Serial No. 324,565.

To all whom it may concern:

Be it known that I, ARTHUR W. HELMHOLTZ, a citizen of the United States, residing at Harrisburg, in the county of Saline and State of Illinois, have invented certain new and useful Improvements in Methods of and Means for Distilling Coal, of which the following is a specification.

This invention relates to a method of and means for distilling coal.

One object of the invention is to improve methods of coal distillation and to improve coke oven constructions and arrangements wherein all or most of the valuable by-products are removed rapidly at low temperature and the fused fuel mass is compressed into a firm mass and any desired part of the remaining gas removed.

Another object is to provide a novel coke oven construction in which associated sections are arranged for continuous or non-interrupted action upon the fuel mass and equipped to perform their functions in an approved manner.

These and other objects are accomplished by means of the coke oven construction disclosed on the accompanying sheet of drawings, in which a longitudinal sectional view of my complete coke oven, and associated vertical and horizontal sections are shown.

In coke ovens heretofore constructed, the carbonaceous material treated therein has had its by-products removed, and the coke formed within the same compartment, making it necessary to heat the oven to an extremely high temperature and to build the chamber long or high to get the desired capacity.

In my improved coke oven construction I have provided two sections, one comprising a vertical retort in which the carbonaceous material is treated in a gravity fed mass at a low temperature for rapidly removing the valuable by-products, and the other comprising a horizontal retort in which the carbonaceous material, which is in a plastic or semi-plastic state, or just beyond this state, but still soft enough to compress rapidly, is treated at a higher temperature and compressed for removing the desired remaining portion of gas and by-products. When the charge of coal or carbonaceous material is moved from the low temperature oven section to a hotter oven section, a better grade of coke may be obtained,

the lower temperature being sufficient to remove the by-products from the coal and causing the material to assume a plastic or semi-plastic condition. The mass may be transferred without lowering the temperature or interrupting the general course of the reaction and compressed in the second oven section so that a fuel of great density may be formed in the hotter portion of the oven, wherein the remainder of the volatile matter, or any portion thereof, may be distilled off by the higher temperatures. Furthermore, by treating the coal at a relatively low temperature in the first stage, metal parts may be used for more rapid heat transmission. In the vertical oven section of relatively low temperature the side oven walls may be heated and in the horizontal oven section the top wall may be heated to a high temperature. Another advantage in having the coke oven divided into two sections is that a relatively short conveyor may be used in the horizontal section, thereby lessening feed trouble; also the vertical section may have a gravity feed, thereby lessening charging difficulties at zones of plasticity.

As indicated above, I prefer my composite oven to take the form of a vertical retort and a horizontal retort properly connected together for continuous treatment of the fuel mass. The main disadvantage in the use of a vertical retort alone as a unit of distillation lies in the looseness of the coke discharge and thereby being unsatisfactory from a finished commercial standpoint. From the standpoint of gravity feed, larger heating surface, by-products, and in speed of distillation, however, the vertical retort is superior to the horizontal type, and at the same time the fuel economy is unsurpassed. To obtain the best results I have combined a vertical retort, wherein the fuel feeds by gravity, with a horizontal retort wherein there is a forced feed. It will be understood that the product from the vertical retort must have sufficient volatile matter left in it to maintain the plastic condition after it enters the horizontal, or tar residues must be added to the mass to make it cohesive. Preferably the fuel mass should enter the horizontal retort having a volatile content of 12 to 13%, which renders it coking. The temperature conditions of the vertical and horizontal retorts are

such that the action on the fuel mass in passing from the vertical to the horizontal retort is a continuous uninterrupted action.

Fig. 1 is a vertical longitudinal section of my oven construction.

Fig. 2 is a cross section on line 2—2.

Referring to the drawings, it will be noted that I have provided an oven construction in which there are two connected sections 10 or retorts 10 and 11, the vertical retort 10 being the low temperature section, in which the by-products are removed, and the horizontal retort 11 being the one in which the plastic mass is compressed to form a firm mass of coke, and in which the desired remaining gases are removed, the two sections 10 and 11 being connected at 12. Coal is fed by gravity into the oven section 10 from a hopper 13 through a chute 14, the flow of the coal being controlled by a valve 15. Flow of material through the vertical retort also may be controlled by the operation of a conveyor 21 in the horizontal retort so that no attendance is required at the inlet of the vertical retort in addition to maintaining the coal supply. This vertical oven section 10 includes two spaced closed walls 9 and 17, the former being within the latter and being the one which receives the coal. The gravity feed of the coal which insures the passage of large amounts of material, is also assisted by increasing the width of the shell 9 at the lower end thereof or its point of discharge. Combustion space or a chamber 18 is formed between the walls whereby the coal within the wall 9 is heat treated, the resulting gas, which is relatively rich, passing out through a gas off-take 19. Gas burners 20 are connected to the combustion space for heating purposes. The closed wall 9 presents a large heating surface which is heated and maintained at a temperature in a manner to heat-treat the coal throughout substantially uniformly for causing rapid distillation of the by-products. The coal which is heat treated in the vertical retort assumes a plastic or semi-plastic condition. In the event too much of the volatile matter of the coal is driven off in the vertical retort, thereby reducing the necessary binder, oil may be supplied to the fuel mass through suitable oil pipes 26, the flow through which may be controlled by valves 27. The fuel mass feeds downwardly by gravity upon a conveyor 21 mounted for a reciprocating movement in the horizontal retort 11, said conveyor being actuated back and forth by a ram 22 having a rod 23 which is connected to the conveyor. When the conveyor 21 is drawn outwardly, the fuel mass or plastic material deposited thereon is prevented from moving in the same direction to the same extent as the conveyor by the bulk head 24 at one end

of the horizontal retort 11, thereby causing the plastic material to be compressed. Accordingly, when the conveyor is given a return movement the coal mass and conveyor move together so that the conveyor can accommodate more coal, the latter being fed automatically by gravity through the vertical retort 10. This compression is caused by the outward stroke of the conveyor, that is as it moves toward the actuating cylinder. The mass of material is plastic and has considerable adhesion to both the conveyor and the walls of the chamber. The conveyor presents a greater area to the mass and hence the adhesion thereto, together with the fact that the weight of the mass is resting upon the conveyor, cause the mass to move with the conveyor. As the outward movement of the conveyor occurs the portion of the material adjacent the bulkhead 24 cannot move with conveyor but is compressed between the bulkhead and the remainder of the mass of material. Some of the completely coked material drops off the far end of the conveyor. As the conveyor moves inwardly the material adjacent the bulkhead 24 moves with the conveyor substantially the length of its stroke and new material drops down from the vertical part of the retort to rest upon the portion of the conveyor which moves inwardly through the bulkhead. As a result of this continuous action, the relative temperatures in the two retorts being properly maintained, the coal in its plastic or semi-plastic condition is conveyed in a compressed state through the horizontal retort 11. The oven section 11 is a flat broad chamber which is heated by an overhead arch structure 29 having an overhead heating passageway 30 fed by gas from ports 31 and 32. The side walls of this oven preferably are heated throughout, the front half of the horizontal length in any suitable manner to assist in the continuous heating action of the fuel mass. Near one end of the oven section 11 at the connection point 12 is a plate 33 inclined in a direction to assist in causing the plastic material to be compressed as it is forced to the discharge end of said oven section. This oven section 11 preferably is provided with a capacity substantially the same as the by-products section or retort 10, or possibly a little smaller to allow for greater compression. Passageways 34 and 35 are provided which lead to the regenerating chambers 36 and 37, respectively, said chambers having outlet and inlet passageways 38 and 39, respectively, leading to a reversing valve not shown. It will be understood that when the conveyor 21 is reciprocated back and forth not only is the coke pressed into a firm mass, but the formed coke is discharged through a chute 41 onto a con-

veyor 42 when the door 43 is moved into an open position. The horizontal retort has a gas offtake 28, the gas passing therethrough being relatively lean. Oil also may be injected into the fuel mass in the horizontal retort 11, as shown at 44 and 45, through pipes 46 and 47, respectively, by any suitable pump system. The horizontal retort having a separate gas outlet and condensing system, the gas recovered at high temperature distillation may be used mainly for heating the walls of both retorts, regenerated air being used in both flue systems to conserve gas and make the combustion system economical.

As mentioned above, it is a well recognized fact that the vertical retort taken alone for completing the coke body falls far short of being satisfactory. Accordingly, instead of having merely a fair grade of coke, I have combined my vertical retort with a cooperating horizontal retort in order that the vertical retort may be used almost entirely for the production of valuable by-products with as much rapidity as possible. This is done by allowing the vertical retort to bring all of the gravity fed fuel mass to a plastic state, or sufficiently beyond this state to still allow of further cementing and handling of the product and pass this heated mass to the highly heated horizontal retort, in which there is a force feed whereby the remainder, or a desired quantity, of the by-products and volatile matter are extracted. By combining the vertical and horizontal retorts as herein disclosed, the lower portion of the usual vertical retort and the front portion of the usual horizontal retort are cut off or eliminated. Accordingly, the plastic or semi-plastic material passing from the vertical retort is immediately presented to the horizontal retort at the zone where the heaviest compression is exerted for compressing the coke at the critical time, which is necessary to produce a compact and dense coke body. The shortened combined systems herein disclosed make it possible to produce readily controlled uniform temperatures so that fuel in the vertical retort is not prevented from reaching vaporizing temperature too late in its downward travel. Oil is preferably injected as indicated in the vertical retort at a point in the fuel body where the temperatures are steady at 900 or 1000° F., the vertical fuel column not being over 1100 to 1200° F. at the point of discharge. The travel of gases in the vertical retort being toward the coal inlet, the vapors from the oil cracking sweep upwardly and present more opportunity for hydrogen atoms to unite with other atoms for producing NH_3 , CH_4 , C_6H_6 , etc. Oil in the hori-

zontal retort, wherein the temperature ranges from 1200 to 1500° F., is introduced at a zone of temperature 1300 to 1400° F., which is preferable for the synthesis of more C_6H_6 , C_6H_5 , CH_3 and $\text{C}_6\text{H}_5\text{OH}$ compounds and creosote components. At the same time the coke surface is improved by a carbon deposit. The amount of oil injected in the horizontal retort is very much less than that injected in the vertical, the ratio being about one to one-half. While I have shown two points for injecting oil into the horizontal retort, oil should be injected into the carbonaceous mass therein only at one point at a time.

By means of this composite oven construction the valuable by-products are removed at a low temperature, thereby making it possible to use metal parts. The fuel is rendered plastic so that during the final heating stage the plastic coal can be pressed into a firm mass and any desired balance of the gas removed. The temperature to which the fuel mass is subjected is increased from the vertical retort through the horizontal retort, thereby causing the action on the fuel mass to be continuous. The conveyor for the horizontal retort is relatively short, thereby lessening the feeding troubles, the fuel mass being fed by gravity from the vertical retort.

It is my intention to cover all modifications of the invention falling within the spirit and scope of the following claims.

I claim:

1. A coke oven comprising two separate sections connected so that carbonaceous material may pass from one section to the other, means for heating the material in the first section to cause it to assume the plastic state, conveying means in the second section comprising a movable carrier receiving the material from the first section in this plastic state, said conveying means acting to compress the material.

2. A coke oven comprising two separate sections connected so that carbonaceous material may pass from one section to the other, the first section being vertical, means for heating the material in the first section to remove by-products and cause it to assume the plastic state, the second section being horizontal, and conveying means comprising a reciprocating carrier adapted to carry the material through this section from the connection with the first section, said conveying means acting to compress the material.

3. A coke oven comprising two separate connected sections for continuous action upon a fuel mass, one of said sections having heated side walls for transmitting heat to carbonaceous material in a mass for extracting by-products therefrom, the other section having a heated top wall for heating

the carbonaceous material to extract further gases and a conveyor adapted to cooperate with a wall of the last mentioned section to cause the compression of the carbonaceous material into a firm mass.

4. A coking system comprising two oven sections, one vertical and the other horizontal, the vertical section being provided with heating means whereby the speed of distillation may be rapid, the by-product recovery being relatively large and the feed of carbonaceous material being by gravity, and means in the horizontal section comprising a conveyor movable lengthwise of the section for compressing the unfinished fuel mass into a firm coke body, means for recovering further heating gases and other by-products and means for controlling the final content of volatile matter in the finished coke.

5. A coke oven comprising two separate connected sections, one being provided with heating means whereby the carbonaceous material may be treated as a mass at a low temperature to remove by-products, and the other being provided with means whereby the carbonaceous material is compressed to form a firm mass of coke, and means for feeding oil to the carbonaceous material to control the volatile content thereof.

6. The method of distilling coal consisting first in heating the coal in a mass at a relatively low temperature for driving off the rich by-products in large quantity, and then heating the carbonaceous material to a higher temperature and compressing same for driving off more by-products and forming a firm mass of coke.

7. The method of distilling coal consisting first in heating the coal in a vertically movable mass at a relatively low temperature for driving off by-products, and then heating the carbonaceous material to a higher temperature and compressing same for driving off more by-products and forming a firm mass of coke.

8. The method of distilling coal consisting first in heating the coal in a gravity fed

mass at a relatively low temperature for driving off the rich by-products, and then heating the carbonaceous material to a higher temperature and mechanically compressing same for driving off more by-products and forming a firm mass of coke.

9. The method of distilling coal consisting first in heating the coal in a mass at a temperature until the mass assumes a plastic condition, during which time by-products are driven off, then heating the plastic mass to a higher temperature for driving off more by-products, and then compressing said mass for forming a firm mass of coke.

10. The method of distilling coal consisting first in heating the coal in a mass until the mass assumes a plastic condition, during which time by-products are driven off, then treating the plastic mass to control its volatile content, and then compressing the mass for forming a firm coke.

11. The method of distilling coal consisting first in heating the coal in a mass until the mass assumes a plastic condition, during which time by-products are driven off, then treating the plastic mass to control its volatile content, and then compressing the mass at a higher temperature.

12. The method of distilling coal consisting first in heating the coal in a mass until the mass assumes a plastic condition, during which time by-products are driven off, then adding oil to the mass to control its volatile content, and then heating the mass at a higher temperature for driving off more by-products.

13. The method of distilling coal consisting first in heating the coal in a mass until the mass assumes a plastic condition, during which time by-products are driven off, then adding oil to the mass to control its volatile content, then heating the mass at a higher temperature for driving off more by-products, and then compressing the mass for forming a firm coke.

Signed at Harrisburg, Ill., this 2nd day of Sept., 1919.

ARTHUR W. HELMHOLTZ.
